UNITED STATES PATENT OFFICE.

JOHN A. MACMAHON, OF PHILADELPHIA, PENNSYLVANIA.

CAR-FENDER MECHANISM.

1,095,650.

Specification of Letters Patent.

Patented May 5, 1914.

Application filed September 21, 1910. Serial No. 583,020.

To all whom it may concern:

Be it known that I, JOHN A. MACMAHON, a subject of the King of Great Britain, residing in the city and county of Philadelphia, 5 State of Pennsylvania, have invented a new and useful Car-Fender Mechanism, of which the following is a specification.

This invention relates to fenders or guards for trolley cars or the like and more particularly to an improvement in trip and drop scoop fenders, such for example as shown in my former application, Serial No. 568,652, filed June 24, 1910 and has for an object to provide a fender wherein the automatic operating mechanism may be rendered inoperative at certain times to prevent dropping of the guard or scoop.

It has been found in practice that snow frequently falls to such a depth, before the 20 snow plows have been put into use, as to cause an obstruction to the free passage of the tripping mechanism, whereby the same is released and the fender or guard lowered. This is of course objectionable and renders 25 the device ineffective and impedes the progress of the car. It has furthermore been found where the track is provided with loops or curves of unusual diameter, that the car is brought so close to the curbing as to 30 project the front of the car over the curb, thus causing the trip to contact therewith and release the guard, whereby either or both the trip and guard may be broken against the curb.

35 In my present invention I have provided a means whereby the operating movement thereof raises the trip and guard so that both are out of the path of any obstruction which would cause damage to the fender or 40 effect an operation thereof at an undesired time.

It further consists of other novel features of construction, all as will be hereinafter fully set forth.

45 For the purpose of illustrating my invention I have shown in the accompanying drawing one form thereof which is at present preferred by me, since the same has been found in practice to give satisfactory and 50 reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a form embodying my invention, showing in dotted lines the abnormal position of the fender when not in use. Fig. 2 represents a detail of construction. Fig. 3 represents a portion of the fender showing the opposite side from that shown in Fig. 1. Fig. 4 represents a detail of the locking and releasing lever. Fig. 5 represents a side elevation of 60 my fender showing in full lines, the normal position of the guard and in dotted lines the operative position of the same. Fig. 6 represents a section on line α — α , Fig. 5.

Similar numerals of reference indicate 70 corresponding parts in the figures.

Referring to the drawings, in the above described figures, the fender is shown as attached beneath the body of the car, thus bringing the scoop into more effective relation to the front wheels of the car, while at the same time the entire fender and its adjuncts are protected from injury, due to collisions and the like, which may occur in the course of ordinary street traffic. Of course 75 the device may be attached to the front of the car, as is customary in the present practice, but such an arrangement is undesirable for the reason that all fenders which are so arranged take up unnecessary space and are 80 exposed to the dangers of traffic.

1 designates the sills of an ordinary car body, to each of which is preferably attached a plurality of hangers 2 forming a supporting means for my novel fender mechanism, 90 said hangers being fixedly secured by means of bolts 3 or equivalent devices in order to correctly position the mechanism with respect to the forward wheels of the car.

4 designates an arm pivotally secured to 95 one of the hangers 2 by means of a rod 5 or the like, thereby supporting one side of the fender mechanism properly in position.

6 designates an arm, in the present instance also pivoted on the rod 5 and serving 100 as a support for the opposite side of the fender and further serving as an adjunct of the tripping mechanism, whereby the fender is dropped to operative position at certain times.

105 The arms 4 and 6 are each provided with a lug 7 for coöperation with extensions 8 of the side arms 9 of the fender, it being apparent that these side arms 9 are each suitably pivoted at 10 to the arms 4 and 6, respectively, thus permitting relative movement between the several parts whereby the 110

fender proper may be folded up when desired.

11 designates the side frames of the fender or guard proper, each of which is provided in the present instance, with an arm 12. The side frames 11 are united to the side arms 9 by means of a rod or tubular member 13, whereby a pivotal movement between the two parts may be effected so that the position indicated in dotted lines may be assumed and the guard raised at certain times.

14 designates a link at each side of the guard, preferably having pivotal connection at 15 to the hanger 2, while its opposite end 15 is united by means of a pin or bolt 16 to a pair of links 17 and 18, the former being provided with a slot 19 with which coöperates the pin 20 fixedly secured to the arm 12, while the latter is attached at its outer end 20 to the tubular member 13, as will be apparent, and forms an element to bring the fender into operative drop position.

21 designates a locking member pivotally secured, as here shown, to the link 18 and having a notched end 22 for engagement with the pin 20. This locking member is also provided with a cam like finger 23, preferably positioned between a pair of pins 24 on the side arm 9, whereby the member 30 12 may be released to allow the fender to assume the dotted line position at the proper time.

25 designates a link pivotally secured at 26 to one of the extensions 8 and connected 35 at its other end by a pin 27 or the like with the lever 28 pivotally mounted on the hanger 2 or other suitable fixed point, said lever being operated by a rod 28^x connected in the present instance to a bell crank 38, to which 40 the control bar 39 is secured.

A pin 39^x or the like is preferably provided to lock the above described parts when the fender is in normal operation upon the car, so that the auxiliary device remains 45 stationary and rigid.

The arm 6 is preferably provided at its forward end with a slot 29 having a notch or recess 30 at one end thereof for coöperation with a pin 31 attached to or forming a 50 part of a link 32. This link 32 forms a part of the trip mechanism and as here shown is pivotally secured at 33 to one of the hangers 2 and has fastened thereto a bar 34 forming a connection between it and 55 the buffer member or trip. This buffer member or trip in the present instance consists of the side arms 35 suitably connected by a suitable buffer rod 35 or the like, positioned to intercept any obstacle which may be upon 60 the track. These arms 35 are pivotally secured at 37 to the hanger 2 and it will be apparent that any motion of these members in a rearward direction will immediately be transmitted to the link 32 and thus 65 move the pin 31 from the notch or recess 30

and allow the pin to be brought into engagement with the cam like surface of the slot 29, thereby effecting a positive movement of the arm 6 and its coöperative adjuncts. In connection with the pin 31 and slot 30 it will be noted that these parts should be very accurately fitted and of suitable material to resist wear at this point, since this connection forms an important part in the stability of the fender, the construction being such that movement of the members is such as shown in Fig. 1 of the drawings. It will thus be clear that when the pin 31 is in the recess 30, the scoop or guard will be positively held in elevated position away from the road bed and the same can only be lowered or dropped by motion of the trip 35 in the direction of the arrows in Fig. 1.

Particular attention is directed to the 85 pivotal connection of the side frames 11 of the scoop or guard to the arms 4 and 6, which in combination with the link construction, give an initial tilting to the scoop member, whereby the same is dropped 90 quickly into close proximity to the road bed. It will be noted that this movement is essential since it brings the fender immediately to its lowermost position ready to receive a body or the like and prevents any 95 portion thereof from getting beneath the guard. After this position has been reached the guard is fixed as far as further lower movement is concerned, the only additional movement being a forward or scooping one 100 bringing the same to the position indicated in dotted lines Fig. 5, in which *g* denotes the ground line.

40 designates a hand or foot lever passing through a suitable opening 41 in the floor of 105 the car and having a plurality of projections 42 thereon adapted to coöperate with a cross bar 43 of one of the hangers 2. This lever 40, as here shown, is pivotally secured at 44 to the link 34 of the trip mechanism, where- 110 by the latter may be operated by the motor- man to drop the scoop or return the parts to normal position after an automatic movement, it being noted that one or the other of the projections 42 engages the cross bar 43 115 and holds the same in raised position. This lever 40 is preferably provided with a spring member 45, whereby the parts are maintained in locked position and cannot be jarred free through movement of the 120 cam.

It will be noted that an essential feature of my invention is the super-normal or above normal position which the device is adapted to assume, thus making three distinct positions of the fender possible, one the normal, the second the operative and the third a 125 position wherein the fender and trip are shifted above the normal position out of the path of any obstructions on the track. 130

In this latter or super-normal position the guard is inoperative relative to a movement of the trip but is however capable of release by the motorman, so that it becomes a 5 gravity operated fender in this position.

In the operation of bringing the trip and guard to super-normal position the motorman raises the lever 40 and removes the trip 35 from tripping position, thereby allowing 10 the fender or guard to drop in front of the wheels of the car and in close proximity to the road bed. As soon as this is accomplished the lever 28 is shifted through the medium of the rod 28^x, thereby moving the 15 link 25 so as to swing the side arms 9 about the pivot 10 and raise the fender frames 11 to the position indicated in dotted lines. During this movement the cam finger 23 contacts with the pins 24, thus releasing the 20 pins 20 and permitting them to move forwardly in the slots 19 so that the parts assume the necessary super-normal position where they are held by suitably fastening the rod 28^x through the medium of the pin 25 39^x until it is desired to lower the guard. By releasing the locking means from the rod 28^x, the guard may be dropped by 25 gravity to operative position.

Attention is directed to the coöperation 30 between the lugs 7 and the extensions 8, as thereby rearward movement of the side arms 9 is prevented and a rigid substantially integral connection formed between the arms 4 and 6.

35 It will now be apparent that I have devised a practical and efficient means of bringing a trip and drop scoop fender mechanism to inoperative position when desired, so that obstructions of a temporary or 40 permanent nature may be avoided and the fender not affected thereby. It will furthermore be apparent that this mechanism does not effect in any way whatsoever the efficient operation of the fender when in use 45 and all the parts thereof perform their functions entirely independent of the shifting mechanism and a fender is provided which may be used or not at the will of the operator of the car.

50 Attention is directed to the advantage of my novel mechanism in connection with fenders located at each end of the car as thereby the rear fender or guard with its tripping mechanism may be raised out of 55 the way and locked in this position until it is desired to bring the same again into operation.

Having thus described my invention, what I claim as new and desire to secure by Letters Patent, is:

1. In a device of the character stated, a guard, a plurality of arms secured to said guard and pivotally mounted on a car, one of said arms having a recess therein, a trip 65 pivotally secured adjacent said recessed

arm, means fixedly mounted on said trip and co-acting in normal position with said recess to form a lock, and an auxiliary device adapted to shift said guard to a predetermined position, whereby said guard is 70 rendered inoperative.

2. In a device of the character stated, a guard, a plurality of arms secured to said guard and pivotally mounted on a car, one of said arms having a recess therein, a trip pivotally secured adjacent said recessed arm, a pin fixedly mounted on said trip and co-acting in normal position with said recess to form a lock, and an auxiliary device adapted to shift said guard to a predetermined position, whereby said guard is 75 rendered inoperative.

3. In a device of the character stated, a guard, arms secured to said guard and pivotally mounted on a car, one of said arms having a recess therein, a trip pivotally secured adjacent said guard arms, a pin on said trip co-acting in normal position with said recess to form a lock, means to lock said guard in its tripped position, and an auxiliary device adapted to shift said guard to a predetermined position, whereby said guard is 80 rendered inoperative.

4. In a device of the character stated, a plurality of arms pivotally mounted on a car, a guard pivoted to said arms, a trip operatively connected to one of said arms to move the same, means to effect a swinging of said guard relative to said arms during the movement of said arms, and an auxiliary device adapted to shift said guard to a predetermined position, whereby said guard is 85 rendered inoperative.

5. In a device of the character stated, a plurality of arms pivotally mounted on a car frame, a guard pivoted to said arms, a trip pivotally secured adjacent said arms, means operated by the movement of said trip to effect a swinging of said guard relative to said arms, and means to shift said 90 guard to a super-normal position, whereby said guard is rendered inoperative relative to said trip.

6. In a device of the character stated, a plurality of arms pivotally mounted on a car frame, a guard comprising a plurality of side bars pivoted to said arms, and side arms pivotally secured to said side bars, means to move said guard to operative position, and independent means to shift said 95 guard to a predetermined position, whereby said guard is rendered inoperative relative to said trip.

7. In a fender adapted to move to normal, operative and super-normal positions, the 100 combination of a guard with a trip operatively connected thereto, and means to shift said guard to super-normal position whereby said guard is rendered inoperative relative to said trip.

8. In a fender adapted to move to normal, operative and super-normal positions, the combination of a guard with a trip operatively connected thereto, means to shift said guard to super-normal position whereby said guard is rendered inoperative relative to said trip, and means to lock said guard in super-normal position.
9. In a fender adapted to move to normal, operative and super-normal position, the

combination of a guard with a trip operatively connected thereto, and means to release said trip from operative relation to said guard in super-normal position, whereby said guard may operate by gravity.

JOHN A. MACMAHON.
